UNITED STATES PATENT OFFICE.

ANDREW J. GOLATA AND LOUIS L. ROBERTS, OF DETROIT, MICHIGAN, ASSIGNEES OF ONE-TENTH TO ARTHUR L. ELLIS, OF DETROIT, MICHIGAN, AND ONE-TENTH TO WILLIAM W. CARSWELL, OF HIGHLAND PARK, MICHIGAN.

INTERNAL-COMBUSTION ENGINE.

1,257,598.

Specification of Letters Patent. Patented Feb. 26, 1918.

Application filed February 10, 1917. Serial No. 147,792.

To all whom it may concern:

Be it known that we, ANDREW J. GOLATA and LOUIS L. ROBERTS, citizens of the United States of America, residing at Detroit, in the county of Wayne and State of Michigan, have invented certain new and useful Improvements in Internal-Combustion Engines, of which the following is a specification, reference being had therein to the accompanying drawings.

This invention relates to internal combustion engines, and the primary object of our invention is to provide an engine wherein the piston arrangement tends to properly balance the crank shaft of an engine, eliminate vibration, and thus insure smooth running and a highly efficient explosive engine.

Another object of our invention is to provide an internal combustion engine with reciprocable inner and outer pistons operable in opposed relation with the outer piston serving functionally as cylinder valves controlling the ignition inlet and exhaust of gases to and from the combustion chambers between the heads of the inner and outer pistons.

A further object of our invention is to provide an explosive engine with a piston arrangement as defined above, wherein no portion of a fresh charge of gas is lost during exhaust, as the explosive mixture admitted to the chambers of the engine is reduced to atmospheric pressure and a fresh charge employed as a scavenging agent.

A still further object of our invention is to provide an engine of the above type wherein the parts are constructed with a view of reducing the cost of manufacture, and at the same time retain those features by which compactness, durability and ease of assembling are secured. With such ends in view, our invention resides in the particular construction to be hereinafter described and then claimed.

Reference will now be had to the drawings, wherein

Figure 1 is a longitudinal sectional view of an engine in accordance with our invention;

Fig. 2 is a vertical sectional view taken on the line II-II of Fig. 1; and

Fig. 3 is a similar view taken on the line III-III of Fig. 1.

In the drawings, 1 denotes a sectional

crank case having suitable alining bearings 55 2 for a crank shaft 3, and said crank shaft has two sets of crank portions 4, a single set of crank portions 5 and centrally located cams 6. The sets of crank portions 4 and 5 are in opposed positions relative to the axis 60 of the crank shaft 3 so that the crank shaft will be properly balanced.

7 denotes cylinders supported by the sectional crank case 1 and these cylinders are provided with jackets 8 and connected by 65 housings 9 and 10. The housing 10 provides a chamber 11 having an intake port 12 for a suitable fuel, as gasoline or kerosene supplied from a carbureting device. The bottom of the chamber 11 has suitable guides 70 13 for valve rods 14 and the top of the chamber has ports providing valve seats 15 for valves 16. The valves 16 are of the puppet type and are normally seated or closed by the expansive force of springs 17 75 arranged on valve rods 14 within the housing 10. Above the chamber 11 are ports 17 communicating with the cylinders 7, said ports being separated by a partition 19, so that the valves 16 may be independently 80 actuated to supply an explosive mixture by means of cams 6 to the cylinders 7 in timed relation to the operation of the pistons in said cylinders. Access is had to the ports 18 for grinding the valve seats 15 through 85 the medium of the detachable cover 20.

In the lower part of the housing 10 is a guide 21 for push rods 22 connected to the valve rods 14, and said push rods are provided with rollers or anti-frictional wheels 90 23 engaging the cams 6, so that the operation of valve 16 may be automatically controlled by the crank shaft 3.

Slidable in the cylinder 7 are pistons or piston valves 24 and the heads of these pistons are provided with intake ports 25 and spark plug openings 26. Intermediate the ends of the pistons 24 are wrist pins 27 protruding into the housings 9 and 10 and connected to said wrist pins and the crank portions 4 of the shaft 3 are connecting rods 28.

Slidable in the outer pistons 24 are inner pistons 29 connected to the crank portions 5 of the shaft 3 by connecting rods 30.

The cylinders 7, contiguous to the lower 105 ends thereof have exhaust ports 31 in communication with a suitable exhaust manifold 32, and the outer pistons 24 are provided

with exhaust ports 33 adapted to register with the exhaust ports 31 of the cylinders 7.

The cylinders 7 and the water jackets 8 thereof are provided with spark plug openings for spark plugs 34, and the spark plug openings 26 of the outer pistons 24 are adapted to register therewith, so that an explosive mixture in the outer piston 24 may be ignited.

10 In operation, one of the valves 16 will establish communication between the chamber 11 and one of the cylinders 7 and as there is a reduction of atmospheric pressure in the cylinder on the downstroke of the outer piston 24, the explosive mixture is drawn into the cylinder. On the return or upstroke of the outer piston 24 the valve 16 is closed, the mixture is slightly compressed until the ports 25 register with the ports 18, at which 15 time the charge or mixture is forced into the outer piston 24 between the head thereof and the head of the piston 29. The charge or mixture is compressed by the pistons 24 and 29 approaching each other and as soon as the 20 opening 26 coincides with the spark plug opening 34 the mixture is ignited and the pistons 24 and 29 driven away from each other. A downward movement of the piston 29 will eventually uncover the exhaust 25 port 33 of the piston 24, while said piston carries the port 33 into registration with the port 31 and the intake of a fresh charge tends to drive the exhaust gases from the combustion chamber.

25 We desire to direct attention to the fact that the ports 18 are of greater depth than the piston ports 25 so that a charge in the upper ends of the cylinders 7 may readily pass into the ports 18 and into the ports 25, thus preventing a charge from being trapped in the upper ends of the cylinders 7. With the pistons in one cylinder coöperating and the ignition in said cylinder timed relative to the ignition in the other cylinder of the 30 engine, the crank shaft 3 will be smoothly driven and more uniform power obtained than if a single piston were used in each cylinder. By constructing the outer pistons to serve functionally as valves, we obtain a higher degree of efficiency than if extra valves were employed for controlling the admission of fuel to the combustion chamber of the outer pistons and we would have it understood that multi-cylinder engines 35 may be constructed embodying principles

of our invention and that the engines may be used for various purposes.

What we claim is:—

1. In an internal combustion engine, cylinders provided with fuel intake ports, a chamber between said cylinders adapted to communicate with the intake ports of said cylinders and provided with a fuel intake port, puppet valves controlling the communication between said chamber and said cylinders, and having rods extending downwardly between said cylinders, a crank shaft having three crank portions for each cylinder, cams on said shaft adapted to operate said valve rods to open said valves, inner and outer pistons slideable one within the other and the outer pistons slideable in said cylinders and provided with intake and exhaust ports, two connecting rods for each outer piston, and a single connecting rod for each inner piston, all of said connecting rods articulating the pistons relative to the crank portions of said crank shaft.

2. In an internal combustion engine, a crank shaft, cylinders provided with fuel intake ports, a housing between said cylinders provided with a chamber adapted to communicate with the intake ports of said cylinder, said chamber having a fuel intake port, valves normally seated on a ported wall of said chamber controlling the admission of fuel to said cylinders, valve rods for said valves extending through said chamber and said housing in proximity to said shaft, cams on said shaft to actuate said valve rods to unseat said valves, springs on said rods in said housing holding said valves normally seated, inner and outer pistons slideable one within the other and the outer pistons slideable in said cylinders and coöperating with the inner pistons in providing combustion chambers, said outer pistons being ported for intake and exhaust purposes, means connecting the outer pistons to said crank shaft, means connecting the inner pistons to said crank shaft, and ignition means adapted for firing fuel in the combustion chambers of said pistons.

In testimony whereof we affix our signatures in presence of two witnesses.

ANDREW J. GOLATA.
LOUIS L. ROBERTS.
